(57) **CLAIM**

The ornamental design for bottom of stand up bag, as shown and described.

DESCRIPTION

FIG. 1 is a perspective view of the bottom of a stand up bag according to a first embodiment of the invention showing our new design.

FIG. 2 is a front view of FIG. 1.

FIG. 3 is a side view of FIG. 1.

FIG. 4 is a bottom view of FIG. 1.

FIG. 5 is a perspective view of the bottom of a stand up bag according to a second embodiment of the invention showing our new design.

FIG. 6 is a front view of FIG. 5.

FIG. 7 is a side view of FIG. 5.

FIG. 8 is a bottom view of FIG. 5.

FIG. 9 is a perspective view of the bottom of a stand up bag according to a third embodiment of the invention showing our new design.

FIG. 10 is a front view of FIG. 9.

FIG. 11 is a side view of FIG. 9.

FIG. 12 is a bottom view of FIG. 9.

FIG. 13 is a perspective view of the bottom of a stand up bag according to a fourth embodiment of the invention showing our new design.

FIG. 14 is a front view of FIG. 13.

FIG. 15 is a side view of FIG. 13.

FIG. 16 is a bottom view of FIG. 13.

FIG. 17 is a perspective view of the bottom of a stand up bag according to a fifth embodiment of the invention showing our new design.

FIG. 18 is a front view of FIG. 17.

FIG. 19 is a side view of FIG. 17.

FIG. 20 is a bottom view of FIG. 17.

FIG. 21 is a perspective view of the bottom of a stand up bag according to a sixth embodiment of the invention showing our new design.

FIG. 22 is a front view of FIG. 21.

FIG. 23 is a side view of FIG. 21.

FIG. 24 is a bottom view of FIG. 21.

FIG. 25 is a perspective view of the bottom of a stand up bag according to a seventh embodiment of the invention showing our new design.

FIG. 26 is a front view of FIG. 25.

FIG. 27 is a side view of FIG. 25.

FIG. 28 is a bottom view of FIG. 25.

FIG. 29 is a perspective view of the bottom of a stand up bag according to a eighth embodiment of the invention showing our new design.

FIG. 30 is a front view of FIG. 29.

FIG. 31 is a side view of FIG. 29.

FIG. 32 is a bottom view of FIG. 29.

FIG. 33 is a perspective view of the bottom of a stand up bag according to a ninth embodiment of the invention showing our new design.

FIG. 34 is a front view of FIG. 33.

FIG. 35 is a side view of FIG. 33.

FIG. 36 is a bottom view of FIG. 33.

FIG. 37 is a perspective view of the bottom of a stand up bag according to a tenth embodiment of the invention showing our new design.

FIG. 38 is a front view of FIG. 37.

FIG. 39 is a side view of FIG. 37; and,

FIG. 40 is a bottom view of FIG. 37.
